UNITED STATES PATENT OFFICE

2,414,277

FLOOR TRUCK

Frederick J. Shepard, Jr., West Newton, and Frank Garbarino, Waltham, Mass., assignors to Lewis-Shepard Company, Watertown, Mass., a corporation of Massachusetts

Application May 31, 1943, Serial No. 489,206

4 Claims. (Cl. 280—49)

1

This invention relates to improvements in floor trucks and the object thereof is to provide a floor truck constructed mainly of non-metallic material and which will be rigid, durable and of relatively lighter weight construction than usual floor trucks.

Usual floor trucks comprise a platform having a rectangular metal frame formed of angle irons, channel bars or associated angle bars constructed to receive the ends of floor boards which extend transversely of the length of the frame. The platforms of such trucks are usually carried by a pair of wheels the shafts of which are mounted in brackets which are welded to the side frames and/or to suitable metal cross girders and by casters the mountings of which are welded to the frame or to metal cross girders. Constructions of this character require a considerable amount of steel or cast iron or forgings which, by reason of the shortage of metal due to war conditions, are difficult to obtain.

One of the objects of the present invention is to provide a truck in which the platform or load carrying means including the floor, the girders and reenforcing members which support it are of wood or other non-metallic materials which are readily available.

Another object of the invention is to provide a floor truck having a platform provided with floor boards of wood, or other non-metallic material, which extend longitudinally of the platform instead of transversely thereof as in previous constructions.

Another object of the invention is to provide novel means for reenforcing the floor boards of the platform to prevent sagging thereof when subjected to heavy loads.

A further object of the invention is to provide means for clamping the floor boards, the transverse girders underlying the floor boards and the wheel units firmly together in such manner as to withstand the racking strains applied to the floor truck when in use.

Usual floor trucks are provided with stake holders located at or adjacent the corners of the platform provided with sockets to receive the vertical members of the push bars by which the truck is manipulated or posts or racks to prevent displacement of portions of the load from the platform. Where the platform is provided with a metal frame such stake holders are secured or welded to the frame at or adjacent the corners thereof. Where floor trucks are provided with wooden supporting girders the stake holders are bolted to the girders in such manner that when

2

in use the wood is under tension and the bolts often torn out as the strain comes along the grain of the wood.

One of the objects of the present invention is to provide stake holders in which when strain is applied the bolts are under tension and the wood under compression thereby avoiding the tearing out of the bolts.

More specifically the invention comprises stake holders having socket members which are formed integral with, by forging, welding, or otherwise, a flat plate adapted to be interposed between or superposed upon the non-metallic platform, the girder, and the base of the mountings of the wheel unit which are all secured firmly together by clamping bolts which pass through the superposed members.

Another object of the invention is to provide a construction in which the stake holders are provided with an anchoring plate having an extension with an integral socket member extending at right angles thereto and preferably extending through the plate and located beyond the end of the platform.

25 These and other objects and features of the invention will more fully appear from the following description and the accompanying drawings and will be particularly pointed out in the claims.

Preferred embodiments of the invention are illustrated in the accompanying drawings, in which,

Fig. 1 is a side elevation of a floor truck having a longitudinal reenforcing beam underlying and engaging one of the longitudinally extending floor boards, preferably the central floor board, and showing the floor boards, the girder, the stake socket members and the mountings for the supporting wheels clamped together by through and through bolts;

Fig. 2 is a plan view of the same;

Fig. 3 is a rear end view of the floor truck illustrated in Figs. 1 and 2;

Fig. 4 is a detail vertical sectional view on line 4—4 Fig. 2;

Fig. 5 is a side elevation of a trussed form of floor truck embodying the invention in which the front end of the truck is supported upon bull wheels and the rear end of the truck upon casters, the platform reenforcing means comprising longitudinally extending beams and transverse girders which underlie and engage the floor boards with the mountings for the wheel supporting units clamped to the superposed members by through and through bolts;

Fig. 6 is a plan view of the construction shown in Fig. 5;

Fig. 7 is a rear end view of the same, the vertical members of the push bar being broken away;

Fig. 8 is a detail vertical sectional view showing the assemblage of the stake holder with the floor boards and transverse girder, with the anchoring plate of the stake holder superposed upon the floor board;

Fig. 9 is a similar view showing the stake holder plate interposed between the floor board and the transverse girder and having an extension projecting beyond the end of the platform with the socket member of the stake holder extending therethrough and welded thereto;

Fig. 10 is a detail side elevation of a modified form of stake holder which differs from that illustrated in Fig. 9 by the provision of flanges which embrace the corner of an outermost floor board, and illustrating the manner in which it is assembled upon the floor board and underlying girder; and,

Fig. 11 is a detail plan view of the construction shown in Fig. 10.

The construction illustrated in Figs. 1-4 comprises a platform having a series of longitudinally extending floor boards 1, preferably of wood but which may be of laminated fibreboard or other suitable non-metallic rigid material. Preferably the floor boards 1 are matched with their adjacent edges connected by tongue and groove construction 2. The floor boards, which desirably are of equal length, are mounted upon transverse front and rear girders 3 and 4 of wood or other suitable non-metallic material. The front end of the platform is supported upon suitable wheel units, such as brackets 5, having flat webs or mountings 6 which are secured to the superposed girder and floor boards by a plurality preferably four through and through bolts 7. The brackets 5 are provided with journals for the shaft 8 of the supporting wheels 9 of any suitable character. The rear end of the platform is supported upon one or preferably two caster units comprising brackets 10 in which the shafts 11 of the respective wheels 12 are journaled. The brackets 10 are mounted on usual ball bearings (not shown) carried by flat base plates 13 which underlie the rear cross girder 4 and bolts 14, which extend through the floor boards 1, the cross girder 4, and the base plate of the caster unit, firmly clamp them together.

In the construction illustrated in these figures and in detail in Fig. 4 stake holders are provided to receive the ends of inverted U-shaped push bars 15 for steering and otherwise manipulating the truck but which, of course, may be employed to receive stakes or racks for preventing displacement of portions of the load which is piled upon the truck.

One of the principal features of the invention is to provide a stake holder construction which is more rigidly anchored to the truck having a flat anchoring plate which is adapted to be secured to the platform by the through and through bolts which clamp the floor boards, the girder, and wheel units together, the construction being such that the material of the floor boards and transverse girder is at all times under compression while the bolts which secure them together are under tension as distinguished from prior constructions in which the end portions of wooden floor boards are subject to tensile strain and the bolts to lateral strains which tend to pull the bolts lengthwise of the floor

boards in the direction of the grain of the wood.

In the construction illustrated in Figs. 1-4 the stake holder comprises a vertical tubular socket member 16 which extends through a central aperture in a rectangular anchoring plate 17 and preferably is welded thereto to provide an integral construction. The anchoring plate 17 is provided with bolt holes so positioned as to permit the passage therethrough of the bolts 14 which clamp the floor board, the girder, and the base of the caster unit together.

As illustrated in Figs. 1-4 the anchoring plate 17 is interposed between the lower face of the floor board 1 and the girder 4 and the socket member which may be a section of pipe extends through both the floor boards and the girder with its lower end resting upon the base of the caster unit and its upper end projecting a short distance above the upper surface of the floor board. The socket member 16 is provided near its upper end with suitable aligned holes to receive a locking pin or bolt 18 for detachably securing the push bar 15 firmly in place. Of course, stakes or racks may be similarly detachably secured in the stake holder.

It will be readily understood that the stake holding members may be similarly interposed between the front girder 3 and the floor boards where it is desired to have stakes, racks, or another push bar at the front end of the truck.

Suitable means are provided for reenforcing the floor boards preferably in the form of a beam 19 which extends longitudinally of the central floor board with the upper surface thereof engaging the floor board and which is secured to the transverse girders 3 and 4 by bolts 18 extending through the floor board, the girders 3 and 4 respectively, and the beam 19. Obviously a plurality of such reenforcing beams may be employed and so located as effectively to reinforce the floor boards of the platform.

Other forms of stake holders are illustrated in Figs. 8 and 9 and still another form in Figs. 10 and 11. In the construction illustrated in Fig. 8 the anchoring plate 17 is superposed upon the upper face of the floor board 1 and the pipe or socket member 16 extends downwardly through the floor boards and the girder 4 and is provided at its lower end with an internal flange to form a base in the socket for the stake or leg of the push bar.

It is sometimes desirable to provide means for holding the stakes beyond the end or ends of the platform. Such a construction is illustrated in Fig. 9 in which the anchoring plate 17 is provided with an extension 20 having a suitable aperture therethrough to fit the pipe or socket member 16, the socket member being secured to the anchoring plate 17 by welding. Of course, the socket member and plate may be formed integral and the socket member may be of any desirable length.

The stake holders may be located in any desirable superposed position with respect to the mountings of the wheel units which will permit the clamping bolts to pass through the bases of the wheel units, the girder, the anchoring plate of the stake holder, and the floor boards, and the anchoring plate may of course be either positioned intermediate of the girder and floor boards or upon the upper face of the floor board as illustrated in Fig. 8.

Another form of stake holder which is adapted to embrace the corner of the outermost floor boards when the wheel unit is mounted beneath

the corner of the platform is illustrated in Fig. 11. This construction may be cast or forged as a unit or may be of welded built-up construction. It comprises a flat anchoring plate 21 adapted to rest upon the end girder and underlie the corner of the outermost floor board 1. It is provided with an integral flange 22 which extends upwardly alongside the edge of the outermost floor board with a thickened extension 23 having a wall 24 which engages the end of the floor board and having a vertical socket member 25 integral therewith extending above and below the extended portion 23. In this construction the lower end of the socket member desirably is provided with an internal flange 26 to form a seat for the lower end of the push bar 15 or stake which is seated in it.

Another embodiment of the invention as applied to a trussed platform is illustrated in Figs. 5, 6, and 7. In this construction the floor boards 27 extend longitudinally and are supported near their rear ends upon a pair of transverse girders 28 and 29 and if desired upon a suitable end girder 30. The floor boards are similarly supported at their front ends upon more narrowly spaced girders 31 and 32. All of these girders in turn are mounted upon and supported by longitudinally extending side beams 33 thereby forming a trussed construction in which the transverse girders engage the lower faces of the floor boards. In this construction the front end portion of the platform is supported upon bull wheels 34, the shaft 35 of which is journaled in suitable brackets 36 having flat bases 37 the ends of which underlie the girders 28 and 29 and engage the under face of the beam 33. Suitable bolts 38, which pass through the superposed bases of the brackets 37, the girders 28 and 29 respectively, and the floor board 27 firmly clamp these superposed members together and provide a very rigid construction.

The end girder 30 is likewise clamped to the beam 33 and floor boards 27 by suitable bolts 39 which desirably pass through each of the floor boards.

In this construction the bull wheels are located well within the edges of the platform, as for example, beneath the second floor board from each side and additional clamping bolts 40 desirably are provided to clamp each of the other floor boards to the transverse girders.

The rear end of the truck is supported upon suitable caster units 41 having wheels 42 of relatively smaller diameter and provided with flat bases 43 which underlie preferably rectangular blocks 44 beneath the ends of the longitudinally extending side beams 33, the transverse girder 31, and the floor boards 27. The anchoring plates 17 of suitable stake holders having socket members 16 are interposed between the girder 31 and the floor boards 27 and the superposed members are rigidly connected together by long bolts 45 which extend through the floor boards, the anchoring plates of the stake holders, the rear girder 31, the beam 33, the blocks 42, and the base 43 of the caster unit, thereby rigidly connecting all of the superposed members firmly together. It will be understood that in this construction other forms of stake holders such as are illustrated in Figs. 9-11 may be employed where it is desired to have the push bar, racks or stakes located beyond the ends of the platform, the anchoring plate being made of suitable dimensions to be interposed between the girder and the floor boards. Obviously stake holders may be provided if de-

sired at either or both ends of the platform with the anchoring plate interposed between the girder and floor boards or superposed upon the floor boards or otherwise positioned in such superposed relation that through and through bolts will rigidly secure all of the superposed members including the wheel mountings rigidly and firmly together.

It will be understood that the particular embodiments of the invention shown and described herein are of an illustrative character and that modifications in construction and arrangement of parts may be made within the spirit and scope of the following claims.

Having thus described the invention, what is claimed as new and desired to be secured by Letters Patent is:

1. A floor truck comprising a platform having a floor of longitudinally extending wooden floor boards, front and rear transverse girders underlying the respective ends of said floor boards, suitable supporting wheel units connected to the end portions of the respective girders including rear caster wheel units having flat metal mountings engaging the under face of the respective ends of the rear girder or girders, a pair of metal stake-holding units each having a vertical tubular stake socket and a flat base engaging the floor in parallelism with and superimposed relation to the flat mounting of the respective caster wheel units there-beneath and a plurality of bolts extending through each wheel mounting, the superposed girder, base of the stake holder and the floor and clamping them firmly together.

2. A floor truck comprising a platform having a floor of longitudinally extending wooden floor boards, front and rear transverse girders underlying the respective ends of said floor boards and flush with the ends thereof, suitable supporting wheel units connected to the respective girders including rear wheel caster units having rectangular flat metal mountings engaging the under face of the respective ends of the rear girder or girders, a pair of stake-holding units each having a vertical tubular stake socket extending through the floor and a flat rectangular base engaging the under face of the corner of the floor in parallelism with and in superimposed relation to the flat mounting of the wheel unit there-beneath and bolts extending through each wheel mounting, the superposed girder, base of the stake holder and floor and clamping them firmly together.

3. A floor truck comprising a platform having a floor of longitudinally extending wooden floor boards, front and rear transverse girders underlying the respective ends of the floor board, suitably spaced wheel-supported brackets underlying the front girder and secured thereto by bolts extending through said floor, girder and bracket, suitably spaced casters having flat metal mountings underlying end portions of the rear transverse end girder and a plurality of clamping bolts extending through the respective caster mountings, girder, and floor firmly clamping the same together, and metal stake-holding members each having a tubular socket provided with a flat anchoring base positioned in superposed relation to said caster mountings and connected to said platform by said clamping bolts.

4. A floor truck comprising a platform having a floor of longitudinally extending wooden floor boards, front and rear transverse girders underlying the respective ends of the floor board, suitably spaced wheel-supported brackets underlying

the front girder and secured thereto by bolts extending through said floor, girder and bracket, suitably spaced casters having flat metal mountings underlying the rear end portions of the rear transverse end girder and a plurality of clamping bolts extending through said caster mountings, girder, and floor firmly clamping the same together, and metal stake-holding members each having a tubular socket provided intermediate of

its length with a flat anchoring base in superposed relation to said caster mountings and located between the girder and floor with the socket extending through alined apertures in the floor and girder and connected to said platform by said clamping bolts.

FREDERICK J. SHEPARD, JR.
FRANK GARBARINO.
